UNITED STATES PATENT OFFICE.

HENRY A. DUNCAN, OF COFFEYVILLE, KANSAS.

AEROPLANE CONTROL MEANS.

Application filed October 23, 1925. Serial No. 64,385.

To all whom it may concern:

Be it known that I, HENRY A. DUNCAN, a citizen of the United States, residing at Coffeyville, in the county of Montgomery and State of Kansas, have invented certain new and useful Improvements in Aeroplane Control Means, of which the following is a specification.

10 My present invention pertains to control means for aeroplanes, and contemplates a step forward in the art by the provision of control means through the medium of which an aviator is enabled with his hand to manipulate the rudder, the elevators, and

15 the ailerons.

To the attainment of the foregoing, the invention consists in the improvement as hereinafter described and definitely claimed.

20 In the accompanying drawings, forming part of this specification:

Figure 1 is a plan view illustrative of the application of my improvement to so much of an aeroplane as is necessary to make clear said application.

25 Figure 2 is a view, partly in elevation and partly in section, the sectional part being taken approximately in the plane indicated by the line 2—2 of Figure 1.

30 Figure 3 is a fragmentary side elevation with a portion in longitudinal vertical section.

Similar numerals of reference designate corresponding parts in all of the views of the drawings.

35 I show in Figure 1 a frame including sides 1 and a floor 2, the said frame being incorporated in or fixed to the fuselage of an aeroplane and the floor 2 referred to being by preference, the cock pit floor in said

40 fuselage.

I also show a rudder 3 and elevators 4, and it will be understood that the said rudders 3 and elevators 4 are located on the aeroplane in the conventional manner or

45 in any other manner compatible with the purpose of my invention. Figure 1 will also be found to contain cables 5 which are designed to lead to ailerons which latter, however, are not illustrated, it being within the purview of my invention to employ ailerons of any suitable character, mounted in any appropriate manner on the aeroplane.

50 In furtherance of my invention, a rock shaft 6 is journaled in the frame sides 1, and is equipped with a crank arm 7, Figure 3, and is also provided with T-heads 8, the ex-

tremities of the latter being connected through cables 9 with the elevators 4, whereby swingable movement of the elevators will attend rocking movement of the shaft 6.

55 Journaled in fore and aft longitudinally disposed bearings 10 and 11 in the fuselage are rock shaft portions 12 and 13, said shaft portions for the sake of lightness being preferably of tubular form. On the rock shaft portion 12 is an upstanding arm 14 to which the cables 5 are connected, and from this it follows that adjustment of the ailerons will accompany rocking of the shaft portion 12 about its axis. A ring 15 connects the shaft portions 12 and 13, and pivotally connected at 16 to the said ring 15 is a yoke 17 carried in fixed relation by a tubular upright 18. Extending longitudinally through the said upright 18 is an upright rock shaft 19 with a T-head handle 20 at its upper end. At its lower end the said rock shaft 19 is appropriately connected with a flexible shaft 21, the said shaft 21 being connected at its lower end to an appropriately mounted rockable member 22 on which is a T-head 23. Said T-head 23 has its end portion connected by crossed cables 24 with the rudder 3, the crossing of the cables 24 being resorted to in order to assure the turning of the aeroplane or the deflection thereof in the direction in which the lever or T-head 20 is swung, as is manifestly desirable.

60 Connected to and extending forwardly from the beforementioned crank arm 7 is a rod 30, having at its forward end a bifurcated portion 31, pivotally connected at 32 to the tubular upright 18. By virtue of this provision it will be manifest that when the yoke 17 and the tubular upright 18 are swung as a unit in the direction of the length of the aeroplane, adjustment of the elevators will attend the said movements of the elements 17 and 18.

65 On lateral movement of the yoke 17, tubular upright 18, shaft portions 12 and 13, and the upright arm 14, adjustment of the ailerons will be effected, and it will be noticed here that the flexible shaft portion 21 while constituting an adequate connection 105 for the transmission of motion to the rudder 3, will readily lend itself to the fore and aft swinging movement of the yoke 17, and the tubular shaft 18, as well as to the lateral swinging or rocking movement of the 110 shaft portions 12 and 13, yoke 17, tubular upright 18 and arms 14.

An important characteristic of my novel control means resides in the fact that it is only necessary for the aviator to use his hand in the manipulation of the rudder, 5 the elevators and the ailerons.

Notwithstanding the capacity of function ascribed to my novel means as shown and described, it will be readily noted that the embodiment illustrated is compact, light in 10 weight, strong, and not likely to become deranged, and from this it follows that my improved means will readily lend itself to aeroplane construction.

I have specifically described, the construction and relative arrangement of the elements in the present and preferred embodiment of my invention in order to impart a full clear, and exact understanding of said embodiment. I do not desire, however, to 20 be understood as confining myself to said construction and relative arrangement of the parts, my invention being defined by my appended claims within the scope of which 25 structural changes and changes in arrangement may be made without involving departure from my invention. For instance while I prefer to employ ball and socket joints between the elements 30, on the one hand, and the yoke 31 and crank 7, on the 30 other, as shown in Figure 1, I may employ at said points any connections consonant with the purpose of my invention without affecting the latter.

Having described my invention, what I 35 claim and desire to secure by Letters-Patent, is:—

1. Aeroplane control means comprising fore and aft rock shaft portions, bearings therefor, an arm on the forward rock shaft 40 portion and adapted to be connected with ailerons, a ring joining said rock shaft portions, an upright tubular portion having a yoke at its lower end pivotally connected to 45 said ring, a shaft journaled in said tubular portion and having a handle at its upper

end, a flexible shaft connected to the lower end of said shaft in the tubular portion, a T-head connected with the lower portion of the flexible shaft and adapted to be connected with a rudder, a rock shaft having 50 arms adapted to be connected with elevators, said shaft also having a crank, and a rod connection between said crank and said tubular upright portion.

2. Aeroplane control means comprising 55 fore and aft rock shaft portions, bearings therefor, an arm on the forward rock shaft portion and adapted to be connected with ailerons, a ring joining said rock shaft portions, an upright tubular portion having a yoke at its lower end pivotally connected to 60 said ring, a shaft journaled in said tubular portion and having a handle at its upper end, a flexible shaft connected to the lower end of said shaft in the tubular portion, a T-head connected with the lower portion of the flexible shaft and adapted to be connected with a rudder, a rock shaft having 65 arms adapted to be connected with elevators, said shaft also having a crank, and a rod connection between said crank and said 70 tubular upright portion; the said rock shaft portions being of tubular form, and the said flexible shaft being connected with the T-head in connection with the rudder through 75 the medium of a rockable member.

3. Aeroplane control means comprising a 80 rockable member, a tubular portion swingably connected with said rockable member, turnable means extending through the said tubular portion, means for connection with a rudder, and a flexible shaft disposed within 85 the rockable member and interposed between and connecting the turnable means and the means for connection with said rudder.

In testimony whereof I affix my signature.

HENRY A. DUNCAN.
